United States Patent Office

Des. 216,356
Patented Dec. 16, 1969

216,356

BEVERAGE BREWING AND DISPENSING UNIT

William M. Bardeau, 44 Princess Margaret Blvd.,
Islington, Ontario, Canada

Filed Feb. 16, 1968, Ser. No. 10,613

Term of patent 14 years

Int. Cl. D7—99

U.S. Cl. D94—3

FIG. 1

FIG. 2

FIG. 3

FIG. 4

FIG. 5

FIGURE 1 is a perspective view of the beverage brewing and dispensing unit taken from the front;

FIGURE 2 is a plan view of the unit of FIGURE 1;

FIGURE 3 is a side elevational view of the unit of FIGURE 1 taken from the right hand side of the unit as viewed in FIGURE 1;

FIGURE 4 is a perspective view of the unit of FIGURE 1 taken from the rear of the unit; and

FIGURE 5 is a side elevational view of the unit of FIGURE 1 taken from the left hand side of the unit as viewed in FIGURE 1.

I claim:

The ornamental design for a beverage brewing and dispensing unit, as shown.
